UNITED STATES PATENT OFFICE

172,723

COMBINATION POCKET KNIFE AND MAGNIFYING GLASS

Emil S. Polk, Scarsdale, N. Y.

Application January 11, 1954, Serial No. 28,442

Term of patent 14 years

(Cl. D22—3)

To all whom it may concern:

Be it known that I, Emil S. Polk, a citizen of the United States of America, residing in the village of Scarsdale, county of Westchester and State of New York, have invented a new, original, and ornamental Design for a Combination Pocket Knife and Magnifying Glass, of which the following is a specification, reference being had to the accompanying drawing, forming part hereof.

Figure 1 is a front elevational view of a combination pocket knife and magnifying glass showing my new design.

Figure 2 is a bottom plan view.

Figure 3 is a front perspective view with parts in extended position.

Figure 4 is a rear perspective view.

I claim:

The ornamental design for a combination pocket knife and magnifying glass, as shown.

No references cited.
